UNITED STATES PATENT OFFICE.

SPIROS C. MARKATOS, OF NEW YORK, N. Y.

SUPPORTING IRON PLATE FOR BOILERS.

Application filed October 6, 1926. Serial No. 139,921.

This invention appertains to novel means for associating an iron plate with a boiler, whereby the iron plate can be disposed in close proximity to the boiler and held in firm position thereon against accidental displacement.

The primary object of the present invention is the provision of novel means for supporting the plate directly by the boiler, whereby necessity of providing extraneous clamps and the like is entirely eliminated.

Another object of the invention is the provision of means for supporting the iron plate directly at the axial center thereof from the boiler itself, said means also tending to support the burner of the plate in central position relative to the plate.

A further object of the invention is the provision of a threaded stud supported directly by the boiler adapted to be received within an axial bore formed on the lower surface of the plate, the stud being so disposed as to form an efficient means for supporting the plate in juxtaposition to the boiler without the necessity of providing any other supporting means.

A further object of the invention is the provision of novel means for adjustably associating the stud with the boiler whereby the distance between the plate and the boiler can be adjusted within certain limits.

A still further object of the invention is to provide improved means for associating an iron plate in close proximity to a boiler to conserve space, which will be of a durable character and which can be readily incorporated with a boiler and plate.

With other objects in view, the invention consists in the novel construction, arrangement and formation of parts, as will be hereinafter more specifically described, claimed, and illustrated in the accompanying drawings, in which drawings:

Figure 1 is a fragmentary side elevation of the boiler showing a hot plate associated therewith with novel means employed for connecting the plate to the boiler, parts of the boiler being shown broken away and in section, the hot plate being shown in diametric section,

Figure 2 is a horizontal section taken on the line 2—2 of Figure 1 looking in the direction of the arrows,

Figure 3 is an enlarged detail sectional view illustrating the means of connecting the hot plate to the boiler,

Figure 4 is a view similar to Figure 1 illustrating a modified form of connecting the plates with the boiler,

Figure 5 is a horizontal section taken on the line 5—5 of Figure 4 looking in the direction of the arrows,

Figure 6 is an enlarged detail section showing the modified form of the means employed for connecting the hot plate with the boiler.

Referring to the drawings in detail, wherein similar reference characters designate corresponding parts throughout the several views the letter A generally indicates a conventional boiler, B the plate for heating the irons and C the novel means for associating and connecting the plate with the boiler A.

As stated the boiler is of the conventional type generally employed in hat cleaning and pressing establishments and as shown in Fig. 1 includes the body 5 having the head 6 connected therewith by means of rivets 7. The head 6 of the boiler at its axial center is provided with a boss 8 having an axially threaded opening 9, clearly shown in Figure 3.

The iron plate B can also be of the usual or ordinary construction and embodies the plate 10 on which the iron or plate has a depending annular flange 11 which can be provided with vent openings 12. In accordance with this invention the lower surface of the plate 10 at its axial center is provided with an internally threaded boss 13 or the boss can be eliminated and the plate itself provided with a suitably threaded aperture. The burner 14 of conventional construction is arranged between the plate 10 and the top of the boiler and this burner is provided with the ordinary gas supply pipe 15 and control cock 16.

The improved means for connecting the plates to the boiler A comprises a plug 20 which is externally threaded and fitted within the opening 9 formed in the boss carried by the boiler. This plug 20 is provided with an axial internally threaded socket 21 for the reception of a stud 22 which is threaded throughout its entire length. The upper end of the threaded stud 22 is thread-

ed into the boss 13 formed on the lower surface of the plate.

In assembling the device, the plug 20 is threaded into the boiler, after which the 5 stud 22 is threaded into the threaded socket 21 of the plug 20 after which the burner 14 is placed on the boiler around the stud and plug 20. The plate B is now placed on the upper end of the boiler and is threaded on 10 the stud 22. The gas pipe can now be placed within the ring and connected with the supply base. The pipe 15 extending out through the openings 12 of the plate prevent rotation of the hot plate and thus holding 15 the same in position is assured. If preferred the flange 11 can be rested on top of the boiler or the plate can be supported entirely by the stud. In Figure 1 of the drawings the flange is shown resting on the 20 boiler while in Figure 4, is shown a slight modified form of this invention a flange is shown above the boiler and entirely supported by the stud, as will be later described. The device forms an efficient means for holding 25 the hot plates in position on the boiler and it is obvious that by such construction that a compact and durable arrangement is provided.

In Figures 4 to 6 inclusive a modified 30 form of supporting means indicated by the reference character D, is shown. In this form the plate B instead of being supported by the axial center of the head 6 of the boiler A, is supported by suitable pipe fittings 35 extending to the side of the boiler. The device D comprises an internally threaded cup 30 which is arranged above the axial center of the boiler between the plate B and the boiler. This cup 30 is provided with a radially extending internally 40 threaded socket 31 for the reception of a pipe or rod 32. This pipe or rod 32 extends through one of the openings 12 in the flange 11 of the plate B and is connected to a vertical length of pipe or rod 33 by the use of 45 a suitable elbow coupling 34. This vertical length of pipe or rod extends down the side of the boiler an appreciable distance and is in turn connected by an elbow coupling 35 with a relatively short length of pipe or rod 36 which is in turn threaded into a boss 37 formed on the side wall of the boiler.

The internally threaded cup 30 receives a 50 threaded plug 38 which is similar to the plug 20 and this plug 38 is likewise provided with an internally threaded socket 39 for the reception of a stud 40. This stud 40 is also threaded throughout its entire length similar to the stud 22 and is threaded into 55 the boss 13 formed on the lower side of the plate 10.

In this form of the invention the burner 14 is supported by the cup and is placed around the stud 40 and after the plate is 60 placed on the stud the gas feed pipe can be

connected with the gas pipe and the pipe 36 to the boiler.

By this arrangement the plate B is supported in substantially the same manner in this form as in the form previously described, the only exception being that the stud 40 is supported in the side of the boiler instead of the top. 70

Changes in details may be made without departing from the spirit or the scope of this 75 invention, but what I claim as new is:

1. The combination with an iron holder and a boiler, of means for supporting the iron holder in superimposed relation to the boiler to conserve space and utilize heat 80 arising from the boiler including a stud mounted in the wall of the boiler and secured to the iron holder.

2. The combination with an iron holder and a boiler, of means for connecting the iron 85 holder in superimposed relation to the boiler comprising a stud secured to the iron holder, and means mounting the stud directly in the wall of the boiler.

3. The combination with an iron holder 90 and a boiler, of means for supporting the iron holder in superimposed relation to the boiler including a supporting stud, means adjustably connecting the stud to the boiler, and means carried directly by the iron holder 95 for receiving the stud.

4. The combination with an iron holder and a boiler, of means for connecting the iron holder to the boiler comprising a supporting stud disposed between the boiler 100 and holder in alignment with the axial centers thereof, the iron holder having an internally threaded boss for receiving the stud, and means for rigidly connecting the stud to the boiler. 105

5. The combination with an iron holder and a boiler, of means for connecting the iron holder in superimposed relation to the boiler comprising a stud threaded throughout the entire length, a plug for adjustably receiving the stud, means for securing the plug to the boiler, and an internally threaded boss disposed on the iron holder 110 for receiving said stud.

6. The combination with an iron holder 115 including a top plate having the lower surface thereof provided with an internally threaded boss and a boiler having its head provided with an internally threaded opening, of means for connecting the iron holder to the boiler comprising a plug fitted within the opening in the head of the boiler, a stud adjustably fitted in said plug and adapted to be threaded into the boss of said iron holder. 120

7. The combination with an iron holder including a hot plate having an internally threaded axially disposed boss on its lower surface, a boiler having the head provided at its axial center with an opening, the wall 125 130

of the opening being threaded, a plug fitted in said opening, having an internally threaded socket, of means for connecting the hot plate to the boiler and in predetermined spaced position relative thereto including a stud threaded in the socket and fitted in said boss.

8. The combination with an iron holder, including a top plate and a burner arranged below the top plate and a boiler, of means for connecting the iron holder to the boiler and for holding the burner centralized relative to the top plate and the boiler.

9. The combination with an iron holder including a top plate and an axially disposed burner arranged below the top plate and a boiler, of means for connecting the iron holder to the boiler including a threaded stud carried by the boiler extending through

the burner and into the top plate of the 20 holder.

10. In combination, a steam boiler, a hot plate arranged in spaced parallel relation with the top of the boiler, a burner arranged in the space between the hot plate 25 and the boiler, and a single element centrally fixed to the top of the boiler and detachably connected to the hot plate.

11. In combination, a vertical steam boiler, a hot plate arranged in vertical spaced relation therewith, a burner arranged in the space between the hot plate and the boiler, and a connector passed centrally through the burner and connected to both the hot plate and the boiler.

In testimony whereof I affix my signature.

SPIROS C. MARKATOS.
